UNITED STATES PATENT OFFICE.

WILLIAM F. WENDT, OF ALTOONA, PENNSYLVANIA.

CAR-DOOR.

SPECIFICATION forming part of Letters Patent No. 791,662, dated June 6, 1905.

Application filed May 12, 1904. Serial No. 207,603.

To all whom it may concern:

Be it known that I, WILLIAM F. WENDT, a citizen of the United States, residing at Altoona, in the county of Blair and State of Pennsylvania, have invented new and useful Improvements in Car-Doors, of which the following is a specification.

This invention relates to car-doors of the type designed particularly for freight-cars, and has special reference to improved car-door mounting or hanging whereby the same may be opened and closed with facility, while at the same time providing an arrangement wherein the door when closed will be seated within the door-opening flush with the side of the car-body.

With these and many other objects, which will more readily appear as the nature of the invention is better understood, the same consists in the novel construction, combination, and arrangement of parts, which will be hereinafter more fully described, illustrated, and claimed.

The essential features of the invention involved in the manner of hanging and fastening the door are necessarily susceptible to some structural modification without departing from the scope of the invention, but the preferred embodiment thereof is shown in the accompanying drawings, in which—

Figure 1 is a fragmentary side view of a car body and door, illustrating the improvements contemplated by the present invention. Fig. 2 is a vertical sectional view on the line 2 2 of Fig. 1. Fig. 3 is a detail elevation of one of the sliding door-hangers. Fig. 4 is a sectional view thereof on the line 4 4 of Fig. 3. Fig. 5 is a detail elevation and projected end view of the threshold-strip carried at the bottom edge of the door. Fig. 6 is a detail elevation and projected end view of the draw-handle. Fig. 7 is a detail elevation and edge view of one of the eyebolts which provides for the pivotal mounting of the draw-handle. Figs. 8 and 9 are elevations and end views, respectively, of the guiding-chain holder. Figs. 10 and 11 are detail elevations of one of the keeper-plates for receiving the bottom-lock keys for the door. Figs. 12 and 13 are side and top views, respectively, of the seal-

fastening for the door. Figs. 14, 15, and 16 are a series of detail elevations of the post-chair. Figs. 17, 18, and 19 are detail views showing the applied position of the post-chair.

Like characters designate corresponding parts in the several figures of the drawings.

In carrying out the invention no change is required in the body of the car nor in the general structure of the door, so for illustrative purposes there is shown in the drawings a portion of an ordinary car-body, designated by the numeral 1 and provided in the side thereof with a door-opening 2, formed with a rabbeted seat 3, in which seat is designed to register the car-door 4, whereby the same when closed will lie flush with the sides of the car-body. This may be plainly seen in Figs. 1 and 2 of the drawings.

The car-door 4 is of the sliding type, but has a compound movement whereby it may be moved laterally into and out of the seat 3, while at the same time having a shifting or sliding movement longitudinally of the car-body to provide for covering and uncovering the door-opening. To provide for this, there is associated with the door 4 a plurality of sliding door-hangers, designated in their entirety by the reference character 5 in Fig. 3 and slidably suspended from the fixed L-shaped track-rail 6, rigidly mounted upon suitable supports 7 upon the car-body above the top of the door-opening 2. Any suitable number of hangers 5 may be employed, and each of the same essentially comprises an upper slide-hook 8, a lower door-plate 9, and an intermediate swinging lever-link 10, pivotally connected with the contiguous ends of the slide-hook and door-plate. The upper slide-hook 8 of each hanger is of an L shape in cross-section, corresponding to the shape of the track-rail 6, and is provided at its terminals with guard-flanges 11, extending about the edges of the track to prevent displacement of the hanger. Below the portion engaged with the track-rail the said slide-hook 8 of each hanger is provided with a pendent bifurcated supporting-arm 12, having a chamfered end 13, corresponding to and matching the complementary chamfered upper end 14 of the door-plate 9, which is bolted or otherwise

suitably fastened to the car-door at or contiguous to the top edge thereof. The intermediate swinging lever-link 10 for each hanger has a pivotal connection at one end, as at 15, 5 with the upper end of the door-plate, an intermediate pivotal connection 16 with the arm 12 of the slide-hook, and at the end opposite the pivotal connection 15 provided with a shouldered stop-head 17, deflected at right angles to the shank of the link and adapted to engage against the outer side of the supporting-arm 12 when the door-plate 9 is hanging in the vertical plane of the slide-hook and the said arm 12, as may be seen from the dotted 10 position of parts in Fig. 4 of the drawings.

The swinging lever-link 10 of one of the slide-hangers is adapted to have connected to the outer end thereof, as at 18, the upper end of an adjusting cable or chain 19, passing 20 through an upper guide ring or loop 20, fitted upon the outer side of the car-door, and also passing through the lower guiding-cable holder 21, mounted upon the car-door below and in the vertical plane of the upper ring 20. 25 The lower end of the cable or chain 19 has attached thereto a lifting-handle 22, and the holder 21 essentially consists of a base-block 23, bolted to the door and provided with bifurcated ends 24, removably receiving the 30 end tongues 25 of a detachable cap-piece 26 at the outer side of the block 23 and forming a part of the guide-opening 27 therethrough.

The door 4 has rigidly fastened to its lower edge, at the outer side thereof, a longitudinally-disposed threshold-strip 28, provided with an upturned base-flange 29, having a series of key-openings 30 therein, each of which receives a bottom-locking key 31, adapted to be seated in a socketed keeper-plate 32, bolted 35 on the car-body directly below the bottom edge or sill of the door-opening. Each of the bottom-locking keys 31 preferably has connected thereto a holding or guard chain 33, attached to the car-body and serving to prevent loss of the key. Any number of the 40 keys 31 may be employed and when engaged with the threshold-strip and the keepers therefor the same necessarily provide a firm bottom fastening which resists any outward 45 strain imposed upon the door at the bottom thereof.

At one edge thereof the door has associated therewith a seal-fastening essentially comprising a pivotal hasp 34, pivoted at one end, 50 as at 35, to the bearing-bolt 36, secured in the edge portion of the car-door. The said hasp 34 is adapted to be swung over a keeper-post 37, mounted in the car-body adjacent to the door-opening and having a latch-opening 38, 55 adapted to receive therethrough in front of the hasp the swinging end of a hook-latch 39. This latch is pivoted at one end, as at 40, upon the body of the hasp and at its other end is provided with an eye 41 for receiving the 60 seal-wire.

To facilitate the handling of the door, there is associated with the same a swinging draw-handle 42 of an approximate U shape and provided at opposite ends with the pintles 43, having terminal retaining-lugs 44, adapted to 70 be inserted through and held at one side of the oblong bearing-eyes 45, provided in the outer ends of the eyebolts 46, fitted in the car-door at spaced points.

When the seal or hasp fastening is unlocked 75 and the bottom-locking keys removed, an outward or lateral pull upon the draw-handle 42 serves to swing the lower end of the door off of the bottom sill and out of the door-opening, with the result of permitting the door to swing from its upper end downward and outward, thereby clearing the side of the car, so that it may be readily slid along upon the track-rail. When the door is to be closed, after sliding back in front of the door-opening a downward pull upon the adjusting-cable through the medium of the lever-links of the handles provides for swinging the upper end of the door back into the seat of the door-opening, and at the same time by moving the lower edge of the door onto the sill the same then becomes seated flush within its opening.

In carrying out the present invention it is preferable to associate with the improvements 95 described a door-post chair, designated in its entirety by the reference-number 50 and essentially comprising a casting having a horizontal base portion 51 and the upstanding and pendent flanges 52 and 53, respectively, extending above and below the base-flange at the opposite edges thereof, as may be best seen in Fig. 15 of the drawings. The base-flange 51 fits on the side sill S and is adapted to form a rest for the lower end of the door-post D. The upstanding flange 52 is bolted directly to the door-post P, while the oppositely-located pendent flange 53 overlaps and is secured to the side sill S. The base-flange 51 is further provided with a perforated lug 100 L, receiving the door-post bolt 54. This structure provides a thoroughly solid mounting for the door-post and renders it free from decay at the base.

Having thus described the invention, what 115 is claimed, and desired to be secured by Letters Patent, is—

1. The combination with a sliding car-door and its opening, of a fixed track arranged above the opening, a sliding hanger comprising a 120 slide-hook engaging the track, a door-plate secured to the door, and a swinging lever-link pivoted at one end to the upper end of the door-plate, at an intermediate point pivoted to the lower end of the slide-hook, and at its 125 free end provided with a laterally-offset stop-head, said hook and plate having matching abutting end portions when in alignment, and an adjusting-cable connected to the free end of the link. 130

2. The combination with a sliding car-door and its opening, of a fixed track, sliding hangers suspending the door from the track, a longitudinally-arranged threshold-strip secured to the bottom edge of the door and provided with a continuous outturned base-flange having a series of spaced key-openings therein, fixed keeper-plates secured to the door-frame below the opening, and bottom-locking keys

adapted to extend through said key-openings to into the keeper-plates.

In testimony whereof I affix my signature in presence of two witnesses.

WILLIAM F. WENDT.
